UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HOOK-SETTING MACHINE.

1,356,760.

Specification of Letters Patent. Patented Oct. 26, 1920.

Application filed January 2, 1917. Serial No. 140,097.

To all whom it may concern:

Be it known that I, PERLEY R. GLASS; a citizen of the United States, residing at Brookline, in the county of Norfolk and State of Massachusetts, have invented certain Improvements in Hook-Setting Machines, of which the following description, in connection with the accompanying drawings, is a specification, like reference characters on the drawings indicating like parts in the several figures.

This invention relates to machines for setting lacing hooks, studs or similar devices and has for its general objects to improve the construction, speed and accuracy of operation of such machines.

In operating at high speed it is desirable to engage the work firmly over a considerable area by the feeding means for in this way the position of the work is accurately controlled and all danger is avoided of distorting the work by pulling it out of shape or otherwise. To this end an important feature of my invention consists in clamp feeding mechanism of novel construction. As herein shown a movable clamping member is provided which takes the place of the usual stationary work table, this member with its coöperating clamping member being swung transversely about a common axis in feeding the work.

Another feature of the invention consists in an improved hook carrying device for receiving the hook from a raceway and inserting it in the work. As herein shown this device includes an anvil plate, the position of which is positively but adjustably determined so that the hook may be presented accurately in line with the upsetting die. In this connection another feature of the invention consists in automatic mechanism for moving the anvil plate to and from operative position constructed and arranged to control the transverse position of the anvil plate throughout its vertical movements to and from setting position.

Still another feature of the invention consists in novel mechanism for separating the hooks in the raceway and transferring them to the anvil plate. From a mechanical standpoint it has been found advantageous so to connect these devices that one operates the other and such construction is herein shown.

These and other features of the invention will be best understood and appreciated from the following description of a preferred embodiment thereof selected for purposes of illustration and shown in the accompanying drawings, in which,—

Figure 1 is a view of the machine in side elevation with certain parts broken away;

Fig. 2 is a similar view in front elevation;

Figs. 3 to 10 inclusive show the hook setting and work feeding instrumentalities in the positions which they occupy at different periods throughout the cycle of the machine;

Fig. 11 is a view in perspective of the hook separating mechanism;

Fig. 12 is a view in perspective of the work feeding mechanism and associated parts; and

Fig. 13 is a view in perspective of the parts which comprise the hook carrier.

The present invention is herein illustrated as embodied in a machine of the general type disclosed in my prior application upon which Letters Patent of the United States No. 1,228,768 were granted June 5, 1917. The driving mechanism and other parts not herein fully shown and which comprise no part of the present invention correspond to similar parts disclosed in my said application.

The machine frame 2 is provided with vertical bearings for a reciprocating plunger 4 carrying at its lower end an upsetting die 6 of the usual construction. The plunger 4 has rigidly secured to it an adjustable collar 14 to which are connected the lower ends of double toggle links 12. These links are connected to the upper double toggle links 10 which are journaled upon a cross pin 8 set in a part of the machine frame. Each of the upper toggle links 10 has a rearwardly extending projection and these are pivotally connected to the forward end of an operating link 16. The link 16 is connected to the upper end of a cam lever 18 pivotally mounted upon a stud 20 in the machine frame and having jaws 19 at its lower end which embrace a cam 24 on the main shaft 22 of the machine. Through the mechanism above described the plunger 4 and the upsetting die 6 are raised and lowered in the proper timed relation.

The lower portion of the frame is pro-

vided with vertical bearings for a reciprocating plunger 90 upon the upper end of which is mounted a hook supporting member 92. The plunger 90 has secured to it a 5 collar 94 carrying a pivoted block by which connection is made to the forward end of a cam lever 96 journaled about a transverse shaft 98 in the machine frame and having forks 100 formed at its rear end which embrace the operating cam 102 on the shaft 22. The cam 102 is so set as to move the hook carrier vertically simultaneously with and in an opposite direction to the movement of the upsetting die 6.

10 The plunger 90 has undercut ways at its upper end, as shown in Figs. 1 and 7 which engage with an annular flange formed in a threaded nut 91. The nut 91 receives the shank of the hook supporting member 92, the vertical position of which may be adjusted by turning the nut 91 to bring the member 92 and the anvil 106 resting in the slots in said member into position opposite the raceway 164. This interengagement of 15 the anvil and the member 92 will insure the lateral alinement of the anvil plate and support it during the setting operation, and is maintained throughout the cycle of the machine. In its upper end the hook plate supporting member 92 is recessed to receive a spring pressed clamping member 93 shaped to engage the crown of the hook and hold the hook in place during the setting operation. A screw 95, engaging a slot in the 20 member 93, limits its vertical movement.

25 An anvil plate 106, shaped to enter the throat of the hook, is supported upon the upper end of a lever 108 by an outwardly and downwardly extending shank. This 30 shank is received in a cut away portion of the hook supporting member 92. By means of this arrangement, the size of the part of the anvil which must pass through the work supporting table is reduced and provision 35 made for the relative displacement of the anvil and the member 92 after the hook has been set and while the parts are still within the opening in the table 46 (see Fig. 10). The upper end of the member 92 is provided with guiding and supporting grooves 40 adapted to receive and support the lateral edges of the anvil plate adjacent to its active end, thus insuring the exact lateral alinement of said plate with the die 6 and 45 supporting it against the force of the setting blow. The vertical lever 108 has at its lower end a pair of slotted plates 110 which straddle the plunger 90 and rest upon a cross pin 112 set in the plunger. The lever 50 108 is thus carried vertically with the plunger 90 and at the same time is permitted to swing about the axis of the pin in the plates 110 to carry the anvil plate 106 into or out of alinement with the spring clamp 93.

55 Movement of the anvil plate in this direc-

tion is effected through a link 114, see Fig. 12, which is pivotally connected to the lever 108 by a pin 113 disposed a short distance below the upper end of the lever. The link 114 has a pair of transversely extending lugs forming bearings for a rod 116 having a collar engaging one end of a compression spring 118 the other end of which bears against one of the lugs upon the link 114. The rod 116, which in effect forms the yielding extension of the link 114, is provided at its rear end with a head 120 which is pivotally connected by a pin 121 to a rocker arm 122 journaled on the transverse shaft 124. The upper end of the rocker arm 122 is connected through a link 126 to an oscillatory cam lever 128 which will be referred to hereinafter. The upper end of the lever 108 is provided with an adjustable stop 107 arranged to engage the surface of the hook supporting member 92 and so determine accurately the inner or hook receiving position of the anvil plate. The movement imparted to the link 114 is sufficient to move the stop 107 inwardly to its limit and then compress the spring 118 so that the lever 108 will be held firmly but yieldingly in place during the upward movement of the plunger 90. While this movement takes place the link 114 will swing about the axis 95 of the pin 121 and the spring 118 will be further compressed although this compression will have no effect upon the position of the anvil plate as will be apparent.

Lacing hooks are supplied to the hook carrier from a hopper 140 which may be of any desired construction. As herein shown, it is provided with a picker plate 142 driven intermittently through a slotted disk 143 by a pin projecting from a gear 144 journaled upon a shaft set in the hopper bracket. The gear 144 meshes with a pinion 146 on the end of a shaft 150 which extends transversely across the rear of the machine and is provided with a driving pulley 152 at its 100 outer end. The pulley 152 is connected through a belt to a small pulley 156 formed on the loose member of the driving clutch. The lacing hooks are delivered to the raceway 160 from the hopper 140 and pass along 105 the raceway by gravity until they reach the separator plate 162. This is shown in Fig. 11 from which it will be apparent that successive lacing hooks are delivered sidewise to the lip of the separator and are then 110 transferred to the lower section 164 of the raceway down which they pass with the hook opening in advance. The separator 162 is oscillated through a link 166 connected at its rear end to the upper end of 115 the cam lever 128 before mentioned. The cam lever 128 is journaled upon the stud 20 and provided at its lower end with forks 132 which receive a block pivotally mounted upon a bracket 134 projecting upwardly 120

60 65 70 75 80 85 90 95 100 105 110 115 120 125 130 135

from the reciprocating slide 60. A portion of the periphery of the separator is provided with gear teeth which mesh with a rack formed upon the horizontal moving 5 transferring member 168. The latter is bored longitudinally to receive a spring pressed pin 170 (see Fig. 1) which is arranged to engage the rear side of each hook released by the separator and push it along 10 the raceway section 164 to set it securely upon the anvil plate 106 where the hook is held by the spring clamping member 93.

The work in which the hooks are to be set is positioned upon the table 46 shown best 15 in Fig. 12, which constitutes also the lower member of a clamp feeding mechanism. The table 46 is supported by a downwardly and rearwardly extending shank 48 having a hub 50 through which passes a rod 36 constituting the axis about which the table 46 20 swings in the feeding operation. The table 46 is bifurcated so that it may be moved close to the setting instrumentalities. Oppositely disposed to the rear branch of the 25 table is the upper clamping member 44 which is substantially coextensive with said rear branch and has also a downwardly and rearwardly extending shank 40 which acts as an edge gage for the work and is provided 30 with a hub to receive the rod 36. The clamp member 44 is fast to the rod 36 and is moved vertically thereby as will presently appear. A pin 42 fast to the shank 40 of the upper clamping member and projecting 35 into a bore in the shank 48 of the table insures the equal and simultaneous movement of the two clamping members. The shank 48 of the table has an upwardly extending arm 52 terminating in a split clamp 54 40 which holds a pin 56. To this pin is connected the forward end of a link 58 which forms a part of the feeding mechanism. The other end of the link is connected to the split end 68 of a link 67 pivotally mounted 45 upon the slide bar 60. The bar 60 has downwardly projecting jaws 62 which embrace a cam 64 on the shaft 22 timed to move the bar 60 forwardly and so swing the clamping members toward the left, as seen 50 in Fig. 12, when it is desired to feed the work. The links 58 and 67 are connected at their common point by a pin 69 and guided in their movement by double radius rods 72 55 which extend from a sleeve 74 rigidly connected to the spacing lever 76. The spacing lever is pivotally mounted upon a stud 70 set in an arm 80 projecting from the machine frame and is urged by a spring 75 rearwardly or toward a position corresponding to a minimum feeding movement. This 60 handle may be held in adjusted position by a pin 81 inserted in the plate 82 (see Fig. 2). As the spacing lever is swung toward the left, as seen in Fig. 12, the axis of the 65 radius rods 72 is moved to such position

that more and more of the motion of the slide bar 60 is transmitted to the work clamping members 44 and 46. The arrangement of the feeding mechanism is shown diagrammatically in my prior patent above 70 identified to which reference may be had for further details of this mechanism.

Vertical movement of the upper clamping member 44 is effected through the rod 36 by mechanism which will now be described. The rod 36 is held against angular movement and provided at its lower end with a head carrying a roller 34. A compression spring 38 bears upon the upper side of the head and against a portion of 80 the machine frame, as shown in Fig. 12, tending to move the clamping member 44 downwardly and into engagement with the work. The roller 34 is arranged to run upon the upper surface of a cam 32 fast 85 upon a horizontal shaft 30 arranged to slide forwardly and rearwardly. The rod 30 is connected through a link 28 to the lower end of an extension 26 formed upon one branch of the cam lever 18. When this 90 lever is moved forwardly at its upper end to depress the upsetting die, the roller 34 is lifted by the cam and the clamping member 44 disengaged from the work. On the other hand when the lever 18 is moved to elevate 95 the upsetting die at the conclusion of the setting operation the low portion of the cam 32 is moved beneath the roller 34 and the spring 38 permitted to lower the member 44 to engage the work. 100

In order to permit the clamping member 44 to be elevated for the insertion of the work, its shank 40 is provided with a rearwardly extending projection 180 arranged to be engaged by a cam 182 fast to a transverse shaft 183. At its outer end the shaft 183 carries a forwardly extending arm 184 to which is connected a treadle rod 185. Depression of the treadle rod turns the shaft 183 and so lifts the clamping member 44 105 temporarily against the compression of the spring 38. This movement, it will be understood, takes place independently of the intermittent lifting of the clamping member caused by the reciprocation of the cam 32. 110

The driving pulley 3 runs loose upon the main shaft and suitable starting and stopping mechanism is provided for clutching and unclutching the pulley to the shaft as desired by the operator. Timing mechanism 115 is also provided by which the machine may be stopped after a predetermined number of complete cycles. This mechanism is not herein described as it forms no part of the present invention. It constitutes the subject-matter of the pending application of A. F. Forbes Serial No. 84,885, filed March 17, 1916. 120

The operation of the machine will now be briefly outlined. The spacing lever 76 130

is moved preliminarily in accordance with the space desired between the hooks and is held in place by a pin 81 set in the spacing plate 82 (see Fig. 2). The upper clamping member 44 is then elevated to permit the insertion of the work, the shank of this member acting as an edge gage as will appear from Figs. 7 and 8. The machine comes to rest with a hook in place upon the anvil plate 106 so that when the machine is started the hook is at once forced upwardly through the work and its barrel clenched against the upsetting die 6 which is simultaneously forced downwardly. During the setting operation, the active end of the anvil plate is supported by the cooperating slots in the member 92. Figs. 7, 8 and 9 indicate successive steps in the operation of inserting and clenching a hook. At the conclusion of the setting operation the upper clamping member 44 is elevated and before the hook is disengaged by the setting instrumentalities the two work clamping members are swung toward the right, as seen in Figs. 2 and 12, and then the upper clamping member is lowered into engagement with the work. As soon as the work is engaged by the clamping members the upsetting die 6 is elevated and the hook carrier lowered. Figs. 3 to 6 show successive steps in the operation of the cycle just discussed. During this time the anvil plate 106 is swung outwardly to disengage the clenched hook, as shown in Fig. 10, such a movement being allowed by the shape of the shank of the anvil and the relation between said anvil and the member 92. This plate is then lowered with the hook carrier, being returned to its initial position where it is received in slots in the member 92 when the hook carrier reaches its lowermost position in alignment with the raceway section 164. During this time the clamping members are moved toward the left, as seen in Figs. 2 and 12, and the work advances to bring the point at which the next hook is to be set into alignment with and between the setting instrumentalities. The final step in the cycle consists in the oscillation of the separator plate 162 whereby a hook advanced into the path of the transerrer 168 is pushed by the latter upon the anvil plate 106.

Having thus described my invention, I claim as new and desire to secure by Letters Patent of the United States:

1. A machine for setting lacing hooks, having, in combination, an upsetting die, and hook inserting means including a reciprocatory plunger, an anvil plate pivotally mounted upon the plunger and maintained normally in line with and above its end, and a supporting member mounted on the plunger constructed and arranged for adjustment toward or from the anvil plate and to support the same in hook setting position.

2. A machine for setting lacing hooks, having, in combination, a reciprocatory plunger, a supporting member adjustably mounted on the end of the plunger, and an anvil plate pivotally mounted on the plunger for movement about an axis beneath the supporting member and adapted to be brought into alignment with the end of the plunger to cooperate with the end of the supporting member in supporting and retaining a lacing hook. 70

3. A machine for setting lacing hooks, having, in combination, a reciprocatory plunger having a bore in its upper end, a rotatable support having interlocking engagement with the plunger and provided with a threaded bore, and a hook supporting member having a threaded shank extending through the bore of the support and into the end of the plunger. 80

4. A machine for setting lacing hooks, having, in combination, a reciprocatory plunger, an anvil plate pivotally mounted thereon, an adjustable stop for determining the operative position of the anvil plate on the plunger, and mechanism including a yielding connection for moving the anvil plate to operative position and holding it there during a part of the reciprocation of the plunger. 90

5. A machine for setting lacing hooks, having, in combination, a plunger having a hook supporting member provided with a clamp for the head of a hook and with a cut-away portion at one side, and an anvil plate disposed opposite to the clamp and having a head portion of similar dimensions to the cross sectional dimensions of the hook supporting member and a downwardly and outwardly extending shank 100 shaped to pass through the cut-away portion of the carrier thereby to reduce the size of the hook supporting portions. 105

6. A machine for setting lacing hooks, having, in combination, a reciprocatory plunger, a hook-sustaining structure connected to and carried by said plunger so as to be movable relatively thereto, an actuator arranged behind said plunger, and a link pivotally connected to said actuator and to 110 said structure to move transversely of said plunger and to move said structure relatively to the plunger, said link being extensible longitudinally and movable independently of its actuator to partake of movement 115 of the plunger. 120

7. A machine for setting lacing hooks, having, in combination, a raceway for hooks, a hook-engaging member arranged to separate a hook in the raceway from the hooks 125 behind it, and hook-feeding means arranged to be operated by said hook-engaging member so as to advance said hook as the hook-separating member moves in the direction opposed to its hook-separating movement. 130

8. A machine for setting lacing hooks, having, in combination, a separator plate having teeth formed in its periphery, a hook transferring member having teeth which mesh with those of the separator plate, a driving means, and a rigid connection between one of said members and said driving means. 5
9. A machine for setting lacing hooks, having, in combination, a raceway for hooks, a separating device arranged to separate a hook in the raceway from the hooks behind it, a feeding device arranged to advance the hook so separated, means arranged to operate one of said devices positively, and yielding means arranged to be actuated by said one to operate the other of said devices resiliently. 10
10. A machine for setting lacing hooks, having, in combination, a reciprocatory plunger having a pivoted anvil plate, a raceway for supplying hooks to the plate, a movable hook separator, an operating lever, means connecting said lever and said separator for operating the latter, and means connecting said lever and said plate for relatively moving the plate and said plunger. 15
11. A machine for setting lacing hooks, having, in combination, hook setting and work feeding instrumentalities including a transversely movable work-engaging device having a portion extending downwardly past the edge of the work to act as an edge gage. 20
12. A machine for setting lacing hooks, having, in combination, hook setting instrumentalities, and work feeding means including a pair of clamping members, the upper of which is provided with a downwardly extending shank arranged to be engaged by the edge of the work and serve as an edge gage. 25
13. A machine for setting lacing hooks, having, in combination, setting devices, a cam lever for operating one of the setting devices, work clamping and feeding members, and mechanism interposed between the cam lever and said members for opening or closing them. 30
14. A machine for setting lacing hooks, having, in combination, setting devices, a work feeding member 44, a cam lever 18 for operating one of the setting devices, a connection 30 to the cam lever, a cam 32, and a connection 36 between the cam and the member 44. 35
15. A machine for setting lacing hooks, having, in combination, setting devices, pivotally mounted work-clamping and feeding members movable from a variable initial position to a fixed final position, and means for opening the clamping members in all initial positions thereof. 40
16. A machine for setting lacing hooks, having, in combination, an upsetting die, a reciprocatory plunger, an anvil plate mov- 45
- ably mounted upon said plunger and arranged to co-act with said upsetting die, hook supplying means, and means arranged to be operated by said hook supplying means for moving said anvil plate relatively to the plunger. 50
17. A machine for setting lacing hooks, having, in combination, an upsetting die and hook inserting means including a reciprocatory plunger, an anvil plate movably mounted upon said plunger and arranged to be brought into and out of alinement therewith, work feeding instrumentalities, means for operating said instrumentalities, and means controlled by said operating means for moving said anvil into and out of operative position. 55
18. A machine for setting lacing hooks, having, in combination, an upsetting die, a plunger, a support carried by the plunger, and a hook-carrier carried by and connected to the plunger otherwise than by said support and movable relatively to the plunger and support, said support being adjustable relatively to the plunger to bear against the hook-carrier and thereby to sustain the upsetting stress exerted upon the latter. 60
19. A machine for setting lacing hooks, having, in combination, an upsetting die, hook inserting means including a reciprocatory plunger, an anvil plate pivotally mounted upon the plunger and maintained normally in line with and above its end, and means fixed upon the plunger constructed and arranged to support the active portion of the anvil plate and to assist in retaining a hook thereon. 65
20. A machine for setting lacing hooks, having, in combination, a plunger, a hook-carrier carried by and movable relatively to said plunger, a raceway arranged to conduct hooks to said carrier, a hook-feeder arranged to transfer a hook from said raceway to said carrier, means including an operating lever to impart hook-transferring movement to said feeder, and means operable by said lever for relatively moving said carrier and said plunger. 70
21. A machine for setting lacing hooks, having, in combination, a plunger, a hook-carrier carried by said plunger and movable to and from operative position relatively thereto, a raceway for hooks, a hook-separator arranged to separate a hook from those behind it in the raceway, a hook-feeder arranged to transfer the separated hook from the raceway to said hook-carrier, an actuating lever for operating said hook-separator and said hook-feeder, and means operable by said lever for relatively moving said hook-carrier and the plunger. 75
22. A machine for setting lacing hooks, having, in combination, a raceway for hooks, a hook-separator arranged to act on the hooks in the raceway, a hook-feeder ar- 80
- 85
- 90
- 95
- 100
- 105

- 125
- 130

ranged to advance the hook separated by the separator, a carrier for said hook-feeder relatively to which the latter is arranged to yield, and motion-transmitting means connecting said hook-separator and said carrier to cause them to move in unison.

23. A hook-setting machine comprising, in combination, a hook-setting member, a raceway arranged to conduct hooks thereto, a hook-separator and means for reciprocating the same to release hooks one by one in the raceway, and a hook-feeder arranged to be operated by the separator to transfer the released hooks to the setting member, said separator and said feeder being so related to each other as to cause the advancing movement of the feeder to occur coinci-

dently with the return movement of the separator.

24. A hook-setting machine comprising, in combination, a hook-setting member, a raceway arranged to conduct hooks thereto, a hook-separator and means for reciprocating the same to release hooks one by one in the raceway, and a hook-engaging member operable by the hook-separator and arranged to maintain a hook on the hook-setting member while the hook-separator stands in its retracted or hook-receiving position.

In testimony whereof I have signed my name to this specification.

PERLEY R. GLASS.

It is hereby certified that in Letters Patent No. 1,356,760, granted October 26, 1920, upon the application of Perley R. Glass, of Brookline, Massachusetts, for an improvement in "Hook-Setting Machines," an error appears in the printed specification requiring correction as follows: Page 5, line 99, claim 19, after the word "fixed" insert the word *detachably*; and that the said Letters Patent should be read with this correction therein that the same may conform to the record of the case in the Patent Office.

Signed and sealed this 8th day of March, A. D., 1921.

[SEAL.]

M. H. COULSTON,

Commissioner of Patents.

Cl. 218—17.
